[57] CLAIM

The ornamental design for a double corrugated cardboard table, as shown and described.

DESCRIPTION

FIG. 1 is a front view of the double corrugated cardboard table showing the new design, (a rear view, not shown, is a mirror image of said front view);

FIG. 2 is a top view thereof;

FIG. 3 is a bottom view thereof;

FIG. 4 is a left side view; and,

FIG. 5 is a right side view.
